UNITED STATES PATENT OFFICE

90,827

DESIGN FOR A VEHICLE INDICATOR LIGHT

Henry Witherow, Calumet City, Ill.

Application May 29, 1933. Serial No. 48,235

Term of patent 14 years

To all whom it may concern:

Be it known that I, HENRY WITHEROW, a subject of the British Empire, residing at Calumet City, in the county of Cook and State of Illinois, have invented a new, original, and ornamental Design for a Vehicle Indicator Light, of which the following is a specification, reference being had to the accompanying drawing, forming part thereof.

I claim:

The ornamental design for a vehicle indicator light as shown.

HENRY WITHEROW.
